UNITED STATES PATENT OFFICE.

WALTER V. TURNER, OF EDGEWOOD, PENNSYLVANIA, ASSIGNOR TO THE WESTINGHOUSE AIR BRAKE COMPANY, OF PITTSBURGH, PENNSYLVANIA, A CORPORATION OF PENNSYLVANIA.

FLUID-PRESSURE BRAKE.

1,120,986. Specification of Letters Patent. Patented Dec. 15, 1914.

Application filed July 1, 1911. Serial No. 636,546.

To all whom it may concern:

Be it known that I, WALTER V. TURNER, a citizen of the United States, residing at Edgewood, in the county of Allegheny and State of Pennsylvania, have invented new and useful Improvements in Fluid-Pressure Brakes, of which the following is a specification.

This invention relates to fluid pressure brakes, and more particularly to a brake equipment in which a brake valve is provided at each end of the vehicle, so that the brakes may be controlled from either end of same.

With an equipment of the above character, where the brake valve is of the type employing the well known equalizing discharge valve and piston, if the train pipe pressure is reduced to effect an application of the brakes, the reduction in pressure on the train pipe side of the equalizing piston of the brake valve not in use, causes a reduction in pressure on the equalizing reservoir side of said piston, by leakage past the piston, so that upon increasing the train pipe pressure to release the brakes, the equalizing piston is lifted by the higher train pipe pressure and the discharge valve is thereupon opened to release air from the train pipe. This causes an undesired reduction in train pipe pressure and a consequent loss of time in releasing the brakes, as well as a loss of air. In order to obviate this difficulty, it is customary to provide a cut-out cock in the train pipe connection to the brake valve for cutting off communication from the train pipe to the brake valve not in use on one end of the vehicle. It sometimes happens, however, that the attendant fails to open this cock in going from one end of the car to the other, and as a consequence, when he desires to effect an application of the brakes, he finds that he is unable to do so, by reason of the connection being closed from the brake valve to the train pipe.

The principal object of my invention is to provide means for enabling the operator to secure an emergency application of the brakes even though the cut-out cock is closed, so that service operation can not be effected.

In the accompanying drawing, the single figure is a sectional view of a brake valve device embodying my improvement.

According to the drawing, a brake valve

device of the equalizing discharge type is illustrated comprising the usual casing 1 having a chamber 2, containing rotary valve 3 adapted to be operated by a handle 4 and provided with an equalizing piston 5, subject on one side of the pressure of a chamber 6 open to the usual equalizing reservoir and subject on the opposite side to the pressure of a chamber 7 which is adapted to be connected to the train pipe 8. The equalizing piston 5 is adapted to operate a discharge valve 9 for venting air from the train pipe to the atmosphere.

According to my invention, in addition to the usual train pipe connection 8, an auxiliary train pipe connection 10 is provided which contains a cut-out cock 11 and communicates with the chamber 7 of the equalizing piston 5, the usual train pipe connection 8 having no direct connection with said chamber.

It will now be evident that as the train pipe connection 8 has no cut-out cock, the operator is able at all times to obtain an emergency application of the brakes by the usual manipulation of the brake valve. Therefore, if the operator, after changing ends, fails to open the cut-out cock 11, while he will then be unable to obtain the usual service operation through the action of the equalizing discharge valve mechanism, he can still secure an emergency application of the brakes through the direct train pipe connection 8. It may also be noted that with my improvement applied, by closing the cut-out cock 11, a direct exhaust brake valve is provided for single or two-car operation, while by opening said cock, the equalizing exhaust is made available for longer trains.

Having now described my invention, what I claim as new and desire to secure by Letters Patent, is:

1. In a fluid pressure brake, the combination with a brake valve provided with an equalizing discharge valve mechanism, of two train pipe connections for said brake valve therefor, one of which leads to the equalizing discharge valve mechanism and a cut-out cock in the train pipe connection to the discharge valve mechanism.

2. In a fluid pressure brake, the combination with a brake valve provided with an equalizing discharge valve mechanism, of a direct train pipe connection controlled by

the brake valve, an auxiliary train pipe connection leading to the equalizing discharge valve mechanism, and a cut-out cock in said auxiliary train pipe connection.

5 3. In a fluid pressure brake, the combination with a brake valve provided with an equalizing discharge valve and a piston for operating same, of a direct train pipe connection for the brake valve, an additional 10 train pipe connection leading to one side of said piston, and a cut-out cock in said additional train pipe connection.

4. In a fluid pressure brake, the combination with a brake valve provided with an 15 equalizing discharge valve for venting air from the train pipe and a piston subject to the opposing pressures of the train pipe and an equalizing reservoir for operating said valve, of a train pipe connection 20 adapted to be directly controlled by the brake valve, an additional train pipe connection leading to the train pipe side of said piston, and a cut-out cock in said additional train pipe connection.

25 5. In a fluid pressure brake, the combination with a brake valve device provided with

a rotary valve, an equalizing discharge valve for venting air from the train pipe, and a piston subject on one side to the pressure of an equalizing reservoir and on the opposite side to train pipe pressure for operating 30 said valve, of a train pipe connection controlled by said rotary valve, an additional train pipe connection leading to the train pipe side of said equalizing piston, and a 35 cut-out cock in said additional train pipe connection.

6. In a fluid pressure brake, the combination with a brake valve provided with a manually operated controlling valve and an 40 equalizing discharge valve mechanism, of one train pipe connection leading to the seat of the controlling valve and another train pipe connection leading to said equalizing discharge valve mechanism. 45

In testimony whereof I have hereunto set my hand.

WALTER V. TURNER.
